ELECTRIC STARTING SYSTEM FOR
INTERNAL COMBUSTION ENGINES

Joseph G. Sola, Oak Park, Ill.

Application May 2, 1936, Serial No. 77,486

17 Claims. (Cl. 290—37)

My invention relates to electric starting systems for internal combustion engines comprising an electric starting motor, a battery, and a generator driven by the engine for keeping the battery charged, and particularly to such systems in which the starting motor is automatically thrown into operation and is automatically connected to the engine for cranking it upon the closure of the ignition switch of the engine and is then automatically disconnected when the engine begins to run on its own power, and in which the starting motor is again automatically brought into action for another starting operation, in case the engine dies after a limited number of power strokes, or for restarting the engine in case it becomes stalled at any time during its operation and while the ignition switch still remains closed. It is the object of my invention to provide an improved form and arrangement of parts in a system of this type and comprising a starting switch and actuating mechanism therefor by reason of which an improved operation may be effected, and by which the operation of the starting switch and its actuating mechanism shall be controlled by timing means adapted to operate positively in definitely timed relation to the cooperating parts, the arrangement being such that at each successive step of the operation a substantial margin of power is employed in excess of the minimum required whereby the operation is given the desired positive character so as to avoid the necessity for adjustment of the parts to a high degree of nicety and so as to avoid the necessity for readjustment from time to time to accommodate changing weather conditions.

For preventing the clashing or stripping of the gears by a starting operation, it is highly important that both the engine and the starting motor be at rest or substantially so before the starting mechanism is put into operation. If a starting operation is attempted with the starting motor already rotating at a fairly high speed the pinion on the starting motor shaft is likely to be blocked out of mesh with the fly wheel gear of the engine so as to defeat completely the attempt to throw the parts into effective operation and so as to cause the starting motor and the pinion to rotate idly until the condition is cured by an opening of the ignition switch. If a starting operation is attempted with either the starting motor or the engine already in rotation, a smooth movement of the pinion on the starting motor shaft into mesh with the fly wheel gear of the engine is difficult or impossible and the parts are likely to be damaged. It is accordingly one of the

objects of my invention to provide an improved arrangement of parts by which the operation of the starting mechanism shall be definitely prevented until both the starting motor and the engine are at rest or at least substantially at rest. To this end, it is one of the objects of my invention to provide an improved arrangement of this type in which the means for actuating the starting switch shall be inoperative after a starting operation until both the motor and the engine are at rest, the means for actuating the starting switch being preferably controlled by means which in turn is itself controlled and definitely timed by the rotation of the starting motor and the engine. For carrying out this purpose, it is one of the objects of my invention to provide an improved arrangement comprising electromagnet means for opening a control switch interposed in the circuit between the starting switch mechanism and the battery whereby the starting switch is kept open so long as said electromagnet means is kept effectively energized, and to provide means for connecting said electromagnet means effectively with both the starting motor and the generator so that, so long as either the generator continues to run with the engine or the starting motor continues to rotate by its kinetic energy after being disconnected from the battery and from the engine, said electromagnet means is kept energized so as to prevent the closing of the starting switch until such rotation has ceased.

It is one of the objects of my invention to provide an improved arrangement of this type in which the connection between the battery and the starting motor is arranged with cooperating parts in effect in the form of a Wheatstone bridge, the electromagnet means mentioned above being connected across the bridge adapted by its effective energization to cause the starting switch to open and to remain open. For effecting this result, I have provided an auxiliary resistance means in parallel relation to the starting motor, with the bridging lead including said electromagnet means connected with the starting motor at a point between the field and the armature of the motor and connected with the resistance at such intermediate point therealong as to insure the desired balanced condition. It is one of the objects of my invention to provide an arrangement of this type in which there shall be a fairly weak current through said electromagnet means in one direction after the starting switch has been closed and while the effective resistance of the armature to the flow of current from the

battery therethrough is comparatively small for at least an instant prior to the building up of normal full speed rotation of the starting motor, in which arrangement such weak current in said 5 one direction shall die down completely as the bridge reaches its balanced condition at preferably about the time when full speed rotation of the starting motor under normal full load conditions has been established, and in which there 10 shall be a powerful current in the opposite direction through said electromagnet means from the battery when the bridge is thrown widely out of balance by reason of the greatly increased effective resistance of the armature to the flow 15 of current from the battery therethrough by a reactance effect when the starting motor begins to rotate at highly increased speed as the load is taken off the starting motor due to the rotation of the engine by its own power.

20 It will, of course, be appreciated that while the starting motor is rotating at high speed after the engine has begun to rotate on its own power a heavy current will be sent through the electromagnet means in said connection across the 25 bridge and through one of the arm portions of said auxiliary resistance. It is one of the objects of my invention to provide an arrangement by which a connection is almost instantly effected between said electromagnet means and the 30 starting motor in shunted relation to said auxiliary resistance following the initial rotation of the engine on its own power whereby the electromagnet means and the motor shall be connected by a low resistance circuit so as to insure that 35 the strength of the field in said electromagnet means shall be maintained at a maximum as the speed of rotation of the starting motor decreases after the starting motor has been automatically disconnected from the engine and from the battery, such shunt connection being effected automatically by the influence of the greatly strengthened field in said electromagnet means immediately following the establishment of such field.

It is another object of my invention to improve arrangements of this type in sundry details hereinafter pointed out. The preferred means by which I have accomplished my several objects are illustrated in the accompanying drawing and are hereinafter specifically described. 45 That which I believe to be new and desire to cover by Letters Patent is set forth in the claims.

In the drawing,—

Fig. 1 is a diagrammatic view showing my improved system as applied for starting an internal combustion engine not shown;

Fig. 2 is a diagrammatic view showing in simplified form the bridge arrangement involved in the Fig. 1 connections; and

Fig. 3 is a view showing a fragmentary portion 60 of an internal combustion engine in operative relation to the starting motor of my improved system.

Referring now to the several figures of the drawing, in which corresponding parts are indicated by the same reference characters, 19 indicates a storage battery connected to ground at 11 and connected by means of a lead 12 with the starting motor 13, with a starting switch 14 interposed in the lead between the battery and the motor, the motor being connected to ground at 15. In the arrangement shown, the switch 14 is normally held open by a flat spring 16 and is adapted to be closed by the action of a core 17 operating in a coil 18 connected at one end to 70 ground at 19 and connected at its opposite end 75

by a lead 20 to the lead 12, such lead 20 having a switch comprising contacts 21 and 22 and the ordinary ignition switch 23 included in series therein. A lead 24 to the ignition system of the car is connected with the lead 20 adjacent to the 5 ignition switch 23, and a push button 25 is employed in the arrangement shown in parallel with the switch 21—22. The arrangement is such that when the ignition switch 23 is closed for connecting the ignition system with the battery 10 10 the coil 18 is energized so as to act upon the core 17 and close the starting switch 14 for connecting the motor 13 with the battery 10, as will be readily understood.

The arrangement as shown comprises further a 15 lead 26 connected at one end to the lead 12 and connected at the opposite end to a generator 27 for charging the battery 13 during the operation of the engine, as is usual in arrangements of this type. The generator 27 has the usual mechanical 20 connection with the engine so as to be driven thereby. The generator is connected to ground at 28, and a reverse current relay 29 of any approved type is connected in series in the lead 26 between the battery and the generator.

The means for connecting the starting motor with the engine is to be of the well-known type comprising a pinion 30 slidably mounted on the shaft of the starting motor so as to be rotated by the motor and adapted to be brought automatically into mesh with the gear 31 carried by the fly wheel 32 of the engine, the arrangement being such that the pinion 30 is moved by its inertia along the worm 33 into mesh with the gear 31 against the action of the spring 34 whenever the starting motor is set into operation. For a smooth movement of the pinion into mesh with the gear, both the gear and the pinion should be at rest, or substantially so, just prior to a starting operation.

The means employed by me for controlling the operation of the parts includes an electromagnet which in the arrangement shown comprises a coil 35 mounted upon a core bar 36. In the arrangement shown, the core bar 36 is connected at 45 its lower end with an auxiliary core member 37 in the form of a U upon the arm 38 of which an armature 39 is pivotally mounted. A spring 40 is connected at one end to the armature 39 and at its opposite end to a lug 41 carried by the core 50 member 37, such spring holding the armature normally in raised position with respect to the core bar 36 in the position as shown in Fig. 1 of the drawing.

Upon the arm 42 of the core member 37, I have mounted a yoke 43 upon which a bar 44 is slidably mounted, a spring 45 connected between the slide bar and the yoke being adapted normally to hold the bar at the limit of its upward movement as shown in Fig. 1. The contacts 21 and 22, constituting a switch for opening the lead 20, are mounted upon the yoke 43 and an arm 46 carried by the slide bar 44, whereby the spring 45 serves normally to hold the switch 21—22 closed. As shown in the drawing, the contacts 21 and 22 are insulated from the adjacent parts. Upon the upper end of the slide bar 44, I have provided an arm 47 which is provided at its free end with a contact 48 in position to be engaged by a contact 49 mounted upon the armature 39 at an intermediate point in the operative downward stroke of the armature 39 as hereinafter described. The contact 48 is mounted directly upon the armature 39, while the contact 49 is insulated from the 75

arm 47. The armature 39 at its opposite end is connected to ground as indicated at 50.

For providing a bridge arrangement in connection with the starting motor 13, I have provided an auxiliary resistance member 51 which is connected at one end by a lead 52 to the lead 12 between the starting switch and the starting motor and is connected at its opposite end with ground at 53. By this arrangement, the resistance 51 is placed in parallel arrangement with the starting motor whereby a bridge arrangement is effected by a lead 54 connected at one end with the starting motor between the field coil 55 and the armature 56 and connected at its opposite end with the resistance 51 at an intermediate point therealong by which the resistance is divided into two portions, 51a and 51b. By this arrangement, the two portions 51a and 51b of the resistance comprise the two arms of the bridge at one side thereof and the field and the armature of the motor comprise the two arms of the bridge at the opposite side thereof, all as is shown to advantage diagrammatically in Fig. 2, the coil 35 of the electromagnet being connected in series in the lead 54.

As will be readily understood, when the bridge as above described is in balanced condition, there will be no current passing through the coil 35. As will be further appreciated, the resistance values of three of the arms of the bridge are substantially fixed and unvarying, the effective resistance of the armature 56 only being subject to any substantial variation. The point of connection of the lead 54 with the resistance 51 is such, in my improved arrangement, that the bridge shall be in balanced condition when the starting motor is turning the engine over at normal cranking speed. With the starting motor operating at normal cranking speed, the resistance of the armature with respect to the establishment of a current from the battery therethrough is considerably greater than the resistance of the armature with respect to the establishment of current therethrough from the battery when the motor is at rest or is rotating at a lower speed than the normal cranking speed. It is thus apparent that when the starting switch 14 is first closed for a starting operation there is a small current through the coil 35 in one direction for energizing the electromagnet to a slight extent. Such current through the coil 35 decreases in strength, however, as the speed of the motor increases to its normal value under full load conditions. When later the engine begins to operate on its own power so as to relieve the starting motor of its load, the starting motor then begins to rotate at greatly increased speed, serving to build up very quickly a heavy reactance effect within the armature which serves to cut down very substantially the current from the battery passing through the armature and throwing the bridge widely out of balance. The result is that a heavy current is quickly established through the coil 35 from the battery 10 in the opposite direction from that initially established therein, serving to establish a strong magnetic field through the core parts 36 and 37 in the opposite direction from that initially established when the ignition switch is first closed. This reversal of polarity of the magnet prevents permanent magnetization of the core which might otherwise slowly develop.

In my improved arrangement as shown, the strength of the spring 40 is such that the arma-

ture 39 is held in its raised position against the pull of the electromagnet when energized by a comparatively weak current in the initial direction as above described. When a current of greatly increased strength is sent through the electromagnet coil 35 in the opposite direction, however, as the engine begins to operate on its own power, the armature 39 is given a sharp downward stroke against the action of the spring 40 serving to bring the contact 49 into engagement with the contact 48 and to press the slide bar 44 downwardly against the action of the spring 45 for opening the switch 21-22. This serves to deenergize the coil 18 so as to permit the spring 16 to open the starting switch for disconnecting the battery 10 from the starting motor, this result being effected almost instantly following the initial power stroke of the engine.

For increasing the effectiveness of the coil 35 for the next following step of the operation, I have provided a lead 57 from the contact 48 carried by the armature bar 39 to the lead 54 adjacent to the connection of the lead 54 with the coil 35. By the provision of this lead 57, when the armature 39 moves downwardly, a low resistance circuit connection is established through the leads 54 and 57, the contacts 48 and 49, the armature 39, and the connections to ground at 50 and at 15 between the electromagnet coil 35 and the armature of the motor independently of the other three arms of the bridge and independently of the battery. In the use of my improved system, just as in other starting devices of this type heretofore in use, the starting motor is automatically disconnected from the engine promptly as soon as the engine begins to operate on its own power, this result being effected through the medium of the worm 33 in a well understood manner. As a result of my improved arrangement, as soon as the starting switch 14 opens as above described for disconnecting the motor from the battery so as to permit the motor to function as a generator, current is fed from the starting motor, rotating by its kinetic energy, directly to the electromagnet through the low resistance circuit as specified for keeping such magnet energized so as to hold the armature 39 down as long as the starting motor continues to rotate. With the armature 39 held down so as to hold the switch 21-22 open, the battery 10 is unable under any circumstances to cause the starting switch 14 to close. The starting motor is thus by positive action held out of operation as a motor for effecting a new starting operation until after the rotation of the motor has ceased.

For assuring that the starting motor shall be held out of operation also until after the rotation of the generator 27 has ceased, I have provided a second coil 58 on the core bar 36 connected at one end to the core member 37 for effective connection to ground at 50 and connected at its other end by a lead 59 to the lead 26 between the relay 29 and the generator 27. The coil 58 is made of fairly small wire so as to limit the current loss therethrough whereby the strength of the field produced by the coil 58 is insufficient by a considerable margin for drawing the armature 39 down against the action of the spring 40. The field as produced by the energization of the coil 58 is strong enough however for holding the armature 39 down at the limit of its operative stroke after it has been moved down by the action of the coil 35 so as to insure that the switch 21-22 shall be kept open as long as the generator 27 rotates with the engine. When the engine

is running on its own power after the starting motor has come to rest following the starting operation, the coil 58 serves by itself to hold the armature 39 continuously down so as to prevent the closing of the switch 21—22. When under these circumstances the engine for any reason ceases to operate on its own power, the strength of the field produced by the coil 58 gradually weakens as the speed of rotation of the generator 10 decreases, but the armature is not permitted to move upwardly until the generator comes practically to a full stop.

I have described the bridge as being in balanced condition when the starting motor is turning the engine over at normal cranking speed, and I prefer this particular arrangement though it is not essential. By the use of this arrangement, by reason of which the initial flow of current is in one direction and the later flow is in the opposite direction through the coil 35, the magnetic flux through the core parts 36 and 37 is periodically reversed. The tendency for the core to become permanently magnetized is thus combated and the mechanism is kept at all times in actively operative condition.

It is believed to be unnecessary to describe the operation of the mechanism at length in addition to the references thereto in the description of the apparatus. It will be understood that when the ignition switch 23 is closed, with the parts in the position as shown in Fig. 1, current from the battery 10 is delivered through the leads 12 and 20 to the coil 18 so as to draw the core 17 of the switch starting mechanism toward the right in said Fig. 1 for closing the starting switch. The starting motor 13 is thus thrown into operation, serving to cause the pinion 33 to be shifted into mesh with the gear 31 of the engine so as to crank the engine, and serving to cause the generator 27 also to operate at slow speed. While the starting motor 13 builds up speed in the cranking operation, a weak current flows from the battery 10 across the bridge through the electromagnet coil 35 for establishing a flux in the core, but the attraction is insufficient for causing the armature 39 to move downwardly against the action of the spring 40. When, however, the engine begins to operate on its own power so as to relieve the starting motor of its load and so as to throw the pinion 33 out of mesh with the engine gear 31, the starting motor increases very substantially in speed. This results in a very substantial increase in the resistance to the flow of current from the battery through the armature 56, with the result that the bridge becomes widely unbalanced and a heavy current is caused to flow through the coil 35 in the reverse direction from that in which the current flowed initially through the coil as above described. Upon the establishment of a strong magnetic flux through the core parts 36 and 37 of the magnet in this manner, the armature 39 is drawn sharply downward, bringing the contacts 43 and 49 together and serving to push the slide rod 44 downwardly for moving the contact 21 out of engagement with the contact 22. This results in the demagnetization of the coil 18 so as to permit the spring 46 to open the starting switch 14 for disconnecting the motor from the battery 10. By the engagement of the contact 49 with the contact 48, the coil 35 and the motor are connected together by a low resistance circuit through which current is fed by the starting motor functioning as a generator, such current serving to energize the coil 35. At the same time, the gen-

erator 27 is feeding current to the coil 58 so as to assist the coil 35 in the maintenance of a magnetic flux through the core parts 36 and 37 for holding the armature 39 in its lowered position. The arrangement is such that the spring 40 is not able to raise the armature 39 against the attractive force of the electromagnet until both the generator 27 and the starting motor 13 have come to rest, or substantially so. When the armature 39 moves upwardly, the switch 21—22 is again closed by the spring 45 so as to cause the starting switch 14 again to be closed for a renewed operation of starting the engine. Such renewed starting operation cannot, however, be effected until both the generator 27 and the motor 13 are substantially at rest.

While I prefer to employ the form of arrangement as illustrated and as above described, it is to be understood that my invention is not limited thereto except so far as the narrower claims may be so limited in terms, it being understood that changes in the arrangement may well be made without departing from my invention.

I claim:

1. In a starting means for an internal combustion engine, the combination of a starting motor, means actuated by the operation of said motor for starting the engine, an electric battery, and means comprising an electromagnet energized initially by current therethrough in one direction from said battery and energized much more strongly thereafter when the engine begins to operate on its own power by current therethrough in the opposite direction from said battery for throwing the motor out of operation and energized then by current produced by the continued rotation of said motor by its kinetic energy after a starting operation for preventing the motor from being thrown again into operation until after the motor has come substantially to rest.

2. In a starting means for an internal combustion engine, the combination of an electric starting motor, means actuated by the operation of said motor for starting the engine, an electric battery, means comprising a starting switch for connecting the motor with the battery for operating the motor, and means comprising an electromagnet energized initially by current therethrough in one direction from said battery and energized much more strongly thereafter when the engine begins to operate on its own power by current therethrough in the opposite direction from said battery for opening said starting switch for disconnecting the motor from the battery and energized then by current produced by the continued rotation of said motor by its kinetic energy after a starting operation for preventing the closure of said starting switch until after the motor has come substantially to rest.

3. In a starting means for an internal combustion engine, the combination of an electric starting motor, means actuated by the operation of said motor for starting the engine, an electric battery, means comprising a starting switch for connecting the motor with the battery, electrically operated means comprising circuit means and a normally closed switch therein for closing said starting switch for operating the motor, and means comprising an electromagnet energized by current from said battery for opening said normally closed switch whereby said starting switch is opened for disconnecting the motor from the battery and energized thereafter by current produced by the continued ro-

tation of said motor by its kinetic energy after a starting operation for holding said normally closed switch open so as to prevent the closure of said starting switch until after the motor has come substantially to rest.

4. In a starting means for an internal combustion engine, the combination of an electric starting motor, means actuated by the operation of said motor for starting the engine, an electric battery, means comprising a starting switch for connecting the motor with the battery, electrically operated means comprising circuit means and a normally closed switch therein for closing said starting switch for operating the motor, and
- 10 means comprising an electromagnet energized initially by current therethrough in one direction from said battery and energized much more strongly thereafter when the engine begins to operate on its own power by current therethrough
- 20 in the opposite direction from said battery for opening said normally closed switch so as to permit said starting switch to open for disconnecting the motor from the battery and energized then by current produced by the continued rotation of said motor by its kinetic energy after a starting operation for holding said normally closed switch open so as to prevent the closure of said starting switch until after the motor has come substantially to rest.
- 25 5. In a starting means for an internal combustion engine, the combination of a starting motor, means actuated by the operation of said motor for starting the engine, an electric battery, means comprising an electromagnet energized
- 30 normally by a current from said battery and adapted by a considerably increased current therethrough when the engine begins to operate on its own power to throw the motor out of operation, and means serving when the motor is
- 35 thrown out of operation by said electromagnet to connect said motor and said electromagnet together in a low resistance circuit independently of the battery whereby the current produced by the continued rotation of the motor by its kinetic
- 40 energy keeps said electromagnet energized so long as the motor continues to rotate for preventing the motor from being again thrown into operation.

6. In a starting means for an internal combustion engine, the combination of a starting motor, means actuated by the operation of said motor for starting the engine, an electric battery, means comprising an electromagnet energized initially by current therethrough in one direction from said battery and energized much more strongly by current therethrough in the opposite direction from said battery when the engine begins to operate on its own power serving to throw the motor out of operation, and means

50 serving when the motor is thrown out of operation by said electromagnet to connect said motor and said electromagnet together in a low resistance circuit independently of the battery whereby the current produced by the continued rotation of the motor by its kinetic energy keeps said electromagnet energized so long as the motor continues to rotate for preventing the motor from being thrown again into operation.

7. In a starting means for an internal combustion engine, the combination of an electric starting motor, means actuated by the operation of said motor for starting the engine, an electric battery, means comprising a starting switch for connecting the motor with the battery for operating the motor, means comprising an electro-

magnet energized initially by current therethrough in one direction from said battery and energized much more strongly by current therethrough in the opposite direction from said battery when the engine begins to operate on its own power for opening said starting switch for disconnecting the motor from the battery, and means serving when the starting switch is opened by said electromagnet to connect said motor and said electromagnet together in a low resistance circuit independently of the battery whereby the current produced by the continued rotation of the motor by its kinetic energy keeps said electromagnet energized so long as the motor continues to rotate for preventing the closure of said starting switch.

8. In a starting means for an internal combustion engine, the combination of a starting motor, means actuated by the operation of said motor for starting the engine, an electric battery, means comprising a bridge arrangement for connecting the battery and the motor together, with the field and the armature of the motor forming the two arms of the bridge at one side thereof, electromagnet means connected across the bridge, and means actuated by said electromagnet means when strongly energized for throwing said motor out of operation.

9. In a starting means for an internal combustion engine, the combination of a starting motor, means actuated by the operation of said motor for starting the engine, an electric battery, means comprising a bridge arrangement for connecting the battery and the motor together, with the field and the armature of the motor forming the two arms of the bridge at one side thereof, electromagnet means connected across the bridge, means actuated by said electromagnet means when strongly energized for throwing said motor out of operation, and means

30 serving when said motor is thrown out of operation for connecting the armature of the motor with said electromagnet means in shunted relation to the remaining portions of the bridge whereby the current produced by the continued

35 rotation of the motor by its kinetic energy keeps said electromagnet means energized so long as the motor continues to rotate for preventing the motor from being thrown again into operation.

10. In a starting means for an internal combustion engine, the combination of a starting motor, means actuated by the operation of said motor for starting the engine, an electric battery, means comprising a bridge arrangement for connecting the battery and the motor together, with the field and the armature of the motor forming the two arms of the bridge at one side thereof and with the bridge arranged so as to be in substantially balanced condition when the motor is turning the engine over at normal cranking speed, electromagnet means connected across the bridge, and means actuated by said electromagnet means for throwing the motor out of operation when the engine begins to operate on its own power so as to substantially unbalance said bridge.

11. In a starting means for an internal combustion engine, the combination of a starting motor, means actuated by the operation of said motor for starting the engine, an electric battery, means comprising a bridge arrangement for connecting the battery and the motor together, with the field and the armature of the motor forming the two arms of the bridge at one side thereof, electromagnet means connected

across the bridge, means actuated by said electromagnet means for throwing the motor out of operation when the engine begins to operate on its own power and thus throwing the bridge substantially out of balanced condition by relieving the motor of its load, and means serving when said motor is thrown out of operation for connecting the armature of the motor and said electromagnet means in shunted relation to the remaining portions of the bridge whereby the current produced by the continued rotation of the motor by its kinetic energy keeps said electromagnet means energized so long as the motor continues to rotate and thus prevents the motor 15 from being thrown again into operation.

12. In a starting means for an internal combustion engine, the combination of a starting motor, means actuated by the operation of said motor for starting the engine, an electric battery, circuit means for connecting the battery and the motor together, resistance means connected with the battery in parallel shunt relation to the motor, a lead comprising electromagnet means connected at one end with the motor at a point between the field and the armature of the motor and connected at its opposite end with the resistance means at such a point therealong as to provide a bridge arrangement which is in substantially balanced condition when the motor is turning the engine over at normal cranking speed, and means actuated by said electromagnet means when the engine begins to operate on its own power for throwing the motor out of operation.

13. In a starting means for an internal combustion engine, the combination of an electric starting motor, means actuated by the operation of said motor for starting the engine, an electric battery, circuit means comprising a starting switch for connecting the motor with the battery for operating the motor, resistance means connected with the battery in parallel shunt relation to the motor, a lead comprising electromagnet means connected at one end with the motor at a point between the field and the armature of the motor and connected at its opposite end with the resistance means at such point therealong as to provide a bridge arrangement whereby when said starting switch is closed there is a current through said electromagnet in one direction before the starting motor reaches its normal cranking speed and a greatly increased current through said electromagnet in the opposite direction when the starting motor is rotating at greatly increased speed after the engine has begun to operate on its own power, and means actuated by said electromagnet when the engine begins to operate on its own power for opening said starting switch for throwing the motor out of operation.

14. In a starting means for an internal combustion engine, the combination of an electric starting motor, means actuated by the operation of said motor for starting the engine, an electric battery, circuit means comprising a starting switch for connecting the motor with the battery for operating the motor, resistance means connected with the battery in parallel shunt relation to the motor, a lead comprising electromagnet means connected at one end with the motor at a point between the field and the armature of the motor and connected at its opposite end with the resistance means at such point therealong as to provide a bridge arrangement whereby when said starting switch is closed there is a current through said electromagnet in one di-

rection before the starting motor reaches its normal cranking speed and a greatly increased current through said electromagnet in the opposite direction when the starting motor is rotating at greatly increased speed after the engine has begun to operate on its own power, means actuated by said electromagnet when the engine begins to operate on its own power for opening said starting switch for throwing the motor out of operation, and means serving when the motor is thrown out of operation by said electromagnet to connect said motor and said electromagnet together in a low resistance circuit independently of the battery and independently of the resistance means of said bridge whereby the current produced by the continued rotation of the motor by its kinetic energy keeps said electromagnet energized so long as the motor continues to rotate for holding said starting switch open.

15. In a starting means for an internal combustion engine, the combination of a starting motor, means actuated by the operation of said motor for starting the engine, an electric battery, means comprising a bridge arrangement for connecting the battery and the motor together, with the field and the armature of the motor forming two of the arms of said bridge, electromagnet means connected across the bridge, control means actuated by said electromagnet means when strongly energized adapted by an operative stroke to throw said motor out of operation, means serving when said motor is thrown out of operation for connecting the armature of the motor with said electromagnet means in shunted relation to the remaining portions of the bridge whereby the current produced by the continued rotation of the motor by its kinetic energy keeps said electromagnet means energized so long as the motor continues to rotate for preventing the motor from being thrown again into operation, a generator driven by the engine for charging the battery, and auxiliary electromagnet means electrically connected with said generator for energization thereby adapted when said control means has been given an operative stroke for throwing the starting motor out of operation to hold said control means against a return stroke so long as said generator continues to rotate.

16. In a starting means for an internal combustion engine, the combination of a starting motor, means actuated by the operation of said motor for starting the engine, an electric battery, a control member adapted by an operative stroke in one direction to throw said motor out of operation, an electromagnet energized initially by current therethrough in one direction from said battery and energized much more strongly by current therethrough in the opposite direction from said battery when the engine begins to operate on its own power for giving said control member an operative stroke for throwing the motor out of operation, means serving when the motor is thrown out of operation by said electromagnet to connect said motor and said electromagnet together in a low resistance circuit independently of the battery whereby the current produced by the continued rotation of the motor by its kinetic energy keeps said electromagnet energized so long as the motor continues to rotate so as to prevent the motor from being thrown again into operation, a generator driven by the engine for charging the battery, and auxiliary electromagnet means electrically connected with said generator for energization

thereby adapted when said control means has been given an operative stroke in the direction for throwing the motor out of operation to hold said control means against a return stroke so long as said generator continues to rotate serving thus to prevent the starting motor from being thrown again into operation until said generator has come to rest.

17. In a starting means for an internal combustion engine, the combination of a starting motor, means actuated by the operation of said motor for starting the engine, an electric battery, means comprising a starting switch for connecting the motor with the battery, means for closing said starting switch for throwing the

motor out of operation, means comprising an electromagnet energized normally by a current from said battery and adapted by a considerably increased current therethrough when the engine begins to operate on its own power to open said starting switch for throwing the motor out of operation, a generator driven by the engine for charging the battery, and auxiliary electromagnet means electrically connected with said generator for energization thereby adapted when said starting switch has been opened for throwing the motor out of operation to prevent said switch from being again thrown into operation until said generator has come to rest.
